UNITED STATES PATENT OFFICE.

MAURICE C. RYPINSKI, OF YONKERS, NEW YORK, ASSIGNOR TO C. BRANDES, INC., OF NEW YORK, N. Y., A CORPORATION OF NEW YORK.

TABLE TALKER.

Application filed March 13, 1924. Serial No. 699,090.

To all whom it may concern:

Be it known that I, MAURICE C. RYPINSKI, a citizen of the United States, residing at Yonkers, in the county of Westchester 5 and State of New York, have invented a certain new and useful Improvement in a Table Talker, of which the following is a specification.

My invention relates broadly to electro-magnetic sound reproducers, and more particularly to an instrument for reproducing radio concerts, music and lectures, which I have termed the "table talker."

An object of my invention is to provide 15 a unit assembly for an electromagnetic sound reproducer wherein the acoustic horn is directly connected to the cap, through the agency of a ferrule screwed therein, which cap is screwed over the casing enclosing 20 the electromagnetic operating mechanism in such manner that the entire casing may be set vertically downward into a supporting base and firmly clamped in position.

Still another object of my invention is to 25 provide a construction of electromagnetic sound reproducer casing provided with an annular shoulder and a substantial base member into which the casing may be set vertically downward against an annular 30 flange on the extremity of the base and locked in position facilitating manufacture of the instrument.

Other and further objects of my invention 35 will be understood from the specification hereinafter following by reference to the accompanying drawings, in which:

Figure 1 is a perspective view showing 40 the table talker of my invention; Fig. 2 is a diagrammatic view illustrating the unit assembly which I provide enabling the table talker to be set vertically downward into a supporting base; Fig. 3 is a plan view of 45 the unit assembly illustrated in Fig. 2; and Figs. 4 and 5 show a plan and a side elevation partially broken away indicating the unit assembly of the table talker and its adaptability for vertically downward mounting in a base which may also contain associated apparatus such as a radio receiver 50 or amplifier.

My invention contemplates the unitary structure of the electromagnetic sound reproducer. An annular flange is provided around the top of a screw threaded aperture 55 in the cap on the casing. I provide

a screw threaded ferrule having a shoulder, and when this ferrule is screwed into the cap this shoulder rigidly abuts the aforementioned flange. The ferrule serves as a support for the acoustic horn. The cap is provided with a depending annular skirt with a flange face at its lower extremity. The structure as a whole may then be set vertically downwardly in an especially prepared base having an annular flange face at the top thereof surrounding a central aperture. The flange face of the cap may thus contact with the flange face of the base forming a rigid support.

Referring more particularly to the drawings, reference character 1 indicates the casing which houses the electromagnetic operating mechanism. A screw cap 14 is provided on the casing having an annular depending skirt 15 containing interior screw threads which engage with exterior screw threads on casing 1. The screw cap 14 is thickened in its central portion as represented by reference character 16 and an annular flange 17 provided around a screw threaded aperture in the center of cap 14. A ferrule 20 is screwed into the aperture in the cap 14 and firmly seated against the top surface of flange 17. The ferrule 20 serves as a seat and support for the acoustic horn 22. A flat annular flange 18 is formed on the lower extremity of the skirt 15 of the screw cap 14.

It will be observed that this instrument is complete in itself, the electrical terminals being shown at 19 and 21 connected by flexible leads 23. The complete table talker may be placed vertically downward into the base 30 or base 31 as represented in Figs. 2 and 5.

Heretofore in the art it has been the practice to support the horn directly in a base of some kind and then insert a receiver unit beneath the base in some position where sound might be directed into the horn. This practice is entirely unsatisfactory for quantity production and I have developed the present unit to facilitate production and improve its reproducing characteristics. The base 20 is circular in contour with a flat annular flange 25 at its upper extremity surrounding a central aperture of such size that casing 1 will snugly fit therein. The annular flange 18 on cap 14 makes flat contact with the flat flange 25 of the base giving substantial support. It will be observed

in Fig. 5 that the unit may be fastened within the base by means of a band 32 arranged to draw the inwardly depending tongues 33 of the flange 25 against the casing 1 forming a substantial frictional support. Should it be desirable the base 31 may also contain associated apparatus such as a transformer from which the electromagnetic sound reproducer may be operated from the output circuit of an electron tube amplifier, or radio receiving or amplifying apparatus may be mounted therein.

The present embodiment of my invention has been found to be particularly efficient in operation and practical in construction.

What I claim and desire to secure by Letters Patent of the United States is as follows:

1. An electromagnetic sound reproducer comprising a sound reproducer unit having a substantially cup shaped casing, an electromagnetic operating mechanism contained therein, a screw threaded cap engaging the upper portion of said casing having a flat annular flange substantially above the plane of the lower extremity of said casing, an acoustic horn supported in said cap, a supporting base having a flat central apertured portion of a size slightly greater than the diameter of said casing, a flat annular flange surrounding said apertured portion, a wall extending outwardly from said flange forming a continuation thereof and comprising said supporting base and means for secu-

ing said unit within said apertured portion by a vertically downward movement in which said flat annular flange on said cap contacts with said flat annular flange on said base forming a substantial support for said electromagnetic operating mechanism.

2. An electromagnetic sound reproducer including a sound reproducer unit comprising in combination a substantially cup shaped casing, an electromagnetic operating mechanism carried therein, a screw threaded cap engaging the upper portion of said casing and forming a flat annular flange substantially above the plane of the lower extremity of said casing, an acoustic horn supported in said cap, a supporting base having a diameter substantially larger than the diameter of said cap in the top thereof and having walls tapered to a diameter substantially larger than twice the diameter of said cap, a flat central apertured portion in the top of said base of a size slightly greater than the size of said casing and a flat annular flange formed integral with the wall of said base surrounding said apertured portion, and means for securing said unit within said apertured portion by a vertically downward movement in which said flat annular flange on said cap contacts with said flat annular flange on said base forming a substantial support for said electromagnetic operating mechanism.

MAURICE C. RYPINSKI.
